UNITED STATES PATENT OFFICE.

TANDY MEADOR, OF WESTMORELAND, TENNESSEE.

AUTOMATIC STOVE-DAMPER.

1,143,422.

Specification of Letters Patent. Patented June 15, 1915.

Application filed February 17, 1915. Serial No. 8,809.

To all whom it may concern:

Be it known that I, TANDY MEADOR, a citizen of the United States, residing at Westmoreland, in the county of Sumner and State of Tennessee, have invented certain new and useful Improvements in Automatic Stove-Dampers; and I do hereby declare the following to be a full, clear, and exact description of the invention, such as 10 will enable others skilled in the art to which it appertains to make and use the same.

This invention relates to automatic stove dampers, the principal object of the invention being to secure a uniform temperature 15 in a room, and to utilize the expansion and contraction of the stove pipe for setting the damper which regulates the temperature.

The foregoing and other objects may be attained by means of the construction illustrated in the accompanying drawings, in 20 which—

Figure 1 is a perspective view of an automatic damper made in accordance with this invention, and shown connected to a long 25 pipe to be connected to the stove, Fig. 2 is a view in elevation of the damper regulator and showing the stem for the damper in section, Fig. 3 is a central vertical section through the same, Fig. 4 is a horizontal 30 section through the pipe and showing a portion of the damper broken away, and made on a larger scale than the other views, Fig. 35 5 is a side elevation of the automatic damper, the pipe being shown broken away and the handle for operating the damper being also broken away, and Fig. 6 is a front elevation of the same.

Referring to the drawings, the numeral 1 designates a long pipe, made of a single 40 piece instead of a number of pipe joints, for the reason that expansion of this pipe operates the damper and if made in sections would not operate properly. Connected to the pipe on one side thereof is a curved 45 plate 2 secured by rivets 3 to the pipe 1. Secured within the pipe is an adjustable damper 4, which may be of the usual or any suitable construction provided with an operating rod 5 extending through the pipe 50 and through the plate 2 and provided with a suitable handle 6 for turning the same and adjusting it within the pipe to regulate the draft through the pipe. The operating rod 5 is provided with a rib 7, and the opening 55 in the pipe through which the operating rod 5 passes is provided with a key hole slot,

so that the rib 7 may be pulled out or pushed in beyond the pipe in order to permit the damper to be turned independently of the automatic attachment. A spring 8 encircles 60 the operating rod 5 outside the pipe, one end of said spring bearing against the handle 6 and the other end against a cap 9 which bears against a dial or disk 10, the latter being provided with a radial slot 11 and indicating marks 12 at the side of said slot. A lever 13 is provided with a pin 14 which projects through the slot 11, and the lower end of the lever 13 is offset and is pivoted at 15 to a suitable stud or bearing 16. The offset end 17 of the lever 13 is pivotedly connected at 18 to a rod 19, said rod 19 being mounted in a guide or strap 20 secured to the plate 2, while the lower end of the rod 19 passes through a bearing member 21 and may slide therein and be adjusted 75 in any desired position by means of a binding screw 22. An operating handle 23 preferably formed of some non-heat conducting material is connected to the bearing 21 at 80 its upper end and the lower end is mounted in a collar 24 at the lower end of the pipe 1.

In the disk or dial 10 is an indicating hole 25, and when the groove 27 in the cap 9 is immediately under the hole 25, the rib 7 on the operating rod 5 may be pushed in or withdrawn through the key hole slot in the pipe 1 and in the plate 2 and disk 10. When the handle is pushed in so that the rib 7 is inside the pipe, the damper 4 may be used 85 independently of the automatic attachment. When the rib is outside the pipe and engaged with the key hole slot in the disk 10, the movement of the disk will also move the damper. The disk 10 is also provided with 90 an indicating hole 26 which is disposed on the disk at a point to indicate when the damper is vertical in the pipe.

The operation of the invention may be briefly described as follows: The pin 14 may 100 be adjusted in the slot 11 to any desired temperature which it is required to maintain in the room. When the heat is excessive, the pipe 1 is expanded, and this will rotate the disk and with it the damper 4, 105 and the damper will be practically closed. When the temperature drops to a few degrees below the desired temperature, the damper will be gradually opened until it attains the required temperature when it will 110 be again closed and so on during the time that fuel is placed in the stove or heater.

From the foregoing it will be obvious that a damper regulator made in accordance with this invention is comparatively simple in construction, will be economical in the saving of fuel, and will give the desired temperature and maintain it in a room at all times when there is fire in the stove or heater.

Various changes may be made in the details of construction without departing from the spirit and scope of the invention as defined in the claims.

What is claimed is:—

1. An automatic damper comprising a long pipe, a damper mounted in said pipe and provided with a handle, a spring mounted on the operating rod of the damper outside the pipe, a rib on said operating rod extending through a key hole slot in the pipe, a plate provided with a key hole slot through which said rib extends, and a dial or disk mounted on the operating rod and also provided with a key hole slot for said rib, a spring mounted on the operating rod and bearing against the handle at one end and against the disk at the other end, whereby said damper may be used independently of the attachment, a lever provided with a pin extending through a slot in said dial, means for adjusting said dial to required temperature, and means operated by the expansion and contraction of the pipe for setting the damper at the desired position to give the required temperature.
2. An automatic damper comprising a long pipe, a damper mounted in said pipe

and provided with a handle, a spring mounted on the operating rod of the damper outside the pipe, a rib on said operating rod extending through a key hole slot in the pipe, a plate provided with a key hole slot through which said rib extends, and a dial or disk mounted on the operating rod and also provided with a key hole slot for said rib, a spring mounted on the operating rod and bearing against the handle at one end and against the disk at the other end, whereby said damper can be used independently of the attachment, a lever provided with a pin extending through a radial slot in said disk, a bearing secured to the plate, the lower portion of the lever being pivoted to the bearing, an offset on the lower portion of the lever, a rod pivotally connected to said offset, a guide and a bearing for said rod, said rod slidably mounted in said bearing, a set screw in said bearing, whereby said rod can be adjusted to various positions, a collar secured to the lower part of the pipe, a non-heat conducting operating handle, said handle connected at the upper portion to the rod bearing and at its lower portion secured to said collar, whereby said damper will be operated to the desired position by the expansion and contraction of the pipe.

In testimony whereof I affix my signature in presence of two witnesses.

TANDY MEADOR.
